ROY B. FEHR, OF CLEVELAND, OHIO, ASSIGNOR TO RAIL WELDING & BONDING COMPANY, OF CLEVELAND, OHIO, A CORPORATION OF DELAWARE.

RAIL JOINT AND METHOD OF MAKING.

Application filed January 20, 1924. Serial No. 689,392.

To all whom it may concern:

Be it known that I, Roy B. FEHR, a citizen of the United States, residing at Cleveland, in the county of Cuyahoga and State of Ohio, have invented certain new and useful Improvements in Rail Joints and Methods of Making, of which the following is a specification.

My invention relates to welded rail joints and parts thereof.

It is concerned with a new and improved combination of strength giving features, practices and parts adapted to cooperate in a manner to form a rail joint of greatly improved physical properties including strength, resistance to fatigue and life, as compared with rail joints in use at present.

It is also concerned with a new and improved process of producing a rail joint having the foregoing properties and characteristics.

It is also concerned with the provision of a new and improved joint plate.

The well known need for more durable rail joints, particularly for electric railways in paved streets has for years stimulated the thought of engineers and others to such an extent that the suggested remedies or expedients are practically without number.

So far as I am aware none of these suggestions in itself is capable of accomplishing the solution of the problem, and it appears certain that no suggestion or combination of suggestions ever made has improved the rail joint structure to a point where it

ceased to be a vital problem to the railway engineer. I have made various tests of standard rail joints representative of the most up to date practice of the foremost railway engineers including tests in a repeated impact machine (which tests and machine need not be described herein) and have compared the results with results similarly obtained from rail joints embodying my invention, which comparison indicates marked superiority in physical properties of my joints over those in use up to the time of my invention.

My invention contemplates the utilization of certain old, well known features of construction, and certain new features, and new, or suitably constructed or altered, old parts combined and cooperating with one another and each other to form a substantially uni-

tary rail joint possessing new and improved physical properties. Specifically it contemplates the process for and the construction of a rail joint comprising abutting, aligned rail ends, joint plates on opposite sides of the rail ends, each plate being welded as by the electric arc to the head and base of each rail and each plate having strengthening portions adjacent to the meeting ends of the rails, and means for placing the rail ends under compression and so maintaining them during and after the welding of the plates thereto. Such a joint combines the advantages of plates welded to the rail base throughout their full length with those of plates having reinforcing base flanges throughout their full length but which cannot be welded to the rail base. In other words, I obtain a joint having plates welded to the rail base and also having an increased section modulus at the middle of the plate. My joint also possesses the advantages due to compression of the rail ends against each other as well as those of the staggered arrangement of the plates and welded seams.

The features, practices, configuration of parts and their arrangement and cooperation with each other by which the foregoing and other objects later to be referred to are attained are set forth in the following specification and illustrated in the accompanying drawing forming a part hereof. In the drawings.

Fig. 1 is a side elevation of a rail joint embodying my invention.

Fig. 2 is a cross section taken on line 2—2 of Fig. 1.

Fig. 3 is a top plan view of the joint of Fig. 1.

Fig. 4 is a perspective view of a modified form of joint plate.

Fig. 5 is a perspective view of a joint with an insert between the rails.

Fig. 6 is a section taken on line 6—6 of Fig. 1 showing how the drift pin is used to bring the rail ends together in mutual compression.

In the drawings, 1 indicates each of two abutting rail ends aligned as used in a track, each rail end having a head 2, a base 3 and a web 4. 5 indicates the fish plates arranged on opposite sides of the rail ends adjacent to the web 4 and in contact with the head 2 and base 3 of the rails. Between the ends of

plate 5, I provide a strengthening portion or flange 6 which projects laterally from the base engaging part thereof and serves to increase the section modulus of the plate at 5 the point of maximum stress in a rail joint.

The rail ends are shown as provided with holes 7^a and 7^b extending through the web portion, which are nearly but not quite in alignment with similar holes 8^a and 8^b in 10 plates 5. Tapered drift pins 6^a may be driven through these sets of holes to force the rail ends into moderate compressive engagement with each other. Thus drift pins 6^a may be driven through the sets of holes 15 7^a and 8^a, thereby forcing the rail ends into moderate compressive engagement with each other. While the rail ends, and particularly the ends of the rail heads, are in such a state of mutual compression, the rail bolts 20 (not shown) in holes 7^b and 8^b may be drawn tightly against the plates thus serving to hold the rails and plates in the compressed position. Other bolts may then replace the drift pins and be similarly tightened against 25 the plates. I do not desire too great compression of the rail ends because it may throw too much tensile stress on the plates.

10 indicates the head seam welds between the rail heads and plates, the ends 20 of each weld being spaced some distance from the ends of the plates as shown in Fig. 1. In some cases, it may be desirable to interrupt the seam weld 10 so as to leave unwelded the plates and rail heads immediately 35 adjacent to the abutting faces of the rails, as will be understood without illustration. The base edges of the plates 5 are secured to the base 3 of the rails in a similar manner, as by seam welds 11, the ends of which are 40 similarly spaced from the ends of the plates. These welds are shown as interrupted at the strengthening portion or flange 6 of the rails which extends beyond the edge of the rail base as to prevent welding past it.

45 The upper edge of each plate 5 is provided with a rabbeted recess 9, which, in the form shown in Fig. 2, may extend from the front or outer surface of the plate toward the rear surface in a substantially horizontal plane when the plate is assembled on a rail. The recess 9 preferably extends rearwardly from the edge of and well beneath the rail head, and forwardly of the edge of the rail head, thus constituting a ledge. 50 When the rail and plate are assembled, the recess 9 serves as a substantially horizontally disposed receptacle in which metal may be melted and welded to the outer and under side of the rail head and the top side 55 of the plate. This form of recess retains the molten metal in the desired position and insures a secure connection between wide areas of the plate and head. The form of recess shown in Fig. 2 is that commonly em-

ployed when the said recess is formed as by 65 a shaping or other machining process.

I have found it preferable to make the rabbeted recess 9 of such size that when the plate and rail are in assembled position the greatest distance between the plate and rail 70 may, for example, be approximately $\frac{5}{8}$ ". With a recess of this size and with a ledge formation, an electric arc, such as a carbon arc, moving along the seam will fuse substantially equal areas of the plate and rail, thus making the weld to the rail and to the plate of substantially equal strength, it being understood that the seam weld as a whole will have only the strength provided by the smaller area of contact. It will be 75 further understood that, since rail joints are ordinarily welded when the rails are in position in the track, the welder must necessarily direct the arc angularly and downwardly towards the fish plate and adjacent 80 rail. Under such welding conditions, the provision of a ledge makes much more certain and convenient the obtaining of strong 85 welds having large and equal areas of contact to the rail and plate.

I prefer to position the plates 5 in staggered relation on opposite sides of the rail ends 1, as will be more clearly shown in Fig. 3, so as to obtain a fillet effect on the rail ends at the ends of the plates or a gradual 95 change in section from the rail alone to the rail with both plates. In order that a plate may fit on either side of the rail, I do not locate the strengthening portion, such as flange 6, symmetrically on the plate but offset it from the middle of the plate sufficiently so that it will lie above the meeting faces of the rail bases when used on either side of the rail. The ends of the welded connection or welded seam also are shown as staggered with respect to the plate ends and to 100 each other on opposite sides of the rail.

In Fig. 4 I have illustrated a modified plate 12 embodying my invention, which plate consists of a web portion 13 with a modified form of rabbeted recess 14 on the outer top edge, and cut away at the outer lower edge, as at 15. The modified recess 14 in Fig. 4 is shown as being curved at the rear portion thereof, the recess extending 110 towards the front of the plate in a substantially horizontal plane, or in a slightly downwardly sloped plane as shown in Fig. 4. The form of recess shown in Fig. 4 may, for example, be employed when the recess 115 is formed by a rolling or similar operation, as during the rolling of the plate. Between the ends of the plate is located a strengthening portion 16 so disposed on the plate as to lie above the meeting faces of the rail bases on either side of the rail when the plates are staggered substantially as shown. It will be understood that the strengthening 120 125

portion 16 serves to increase the section modulus of the plate at that point where the bending moment in a joint is at the maximum.

- 5 In Fig. 5 I have shown fragmentarily a rail joint with a gasket like filling member or insert between the rail heads. 17 designates the rails, 18 the plates, and 19 the insert shaped to the outlines of the rail ends. 10 The insert may be only large enough to cover the ends of the rail heads or it may cover a greater part or all of the ends of the rails. In this figure it covers the ends of the heads and extends a short distance 15 above the heads, but when driven down it bears on the top of the plates. A joint constructed with such an insert will have the space or gap between the rail heads substantially filled by the insert. 20 In practicing my invention in one of its forms, I first assemble two rail ends in aligned, abutting position with joint plates on opposite sides thereof in contact with each of the rails, the plates being preferably 25 staggered so that the ends are spaced apart with respect to the length of the rail. I then insert bolts in holes 7^b and 8^b and draw them up snugly but not tightly. Then I drive tapered drift pins through the holes 30 7^a and 8^a in the plates, thereby placing the rail ends, and where the rail ends are suitably prepared, as will be described herein-after, placing particularly the rail heads in a state of mutual moderate compression. 35 The bolts in 7^b and 8^b are then tightened and the drift pins replaced by bolts which are likewise tightened. When I join the plates to the rail by seam welds using preferably the carbon arc process although the metal 40 arc process may be employed in certain cases. It will be understood of course that in either the carbon or metal arc process the metal which may be melted and welded to each rail and plate is usually supplied 45 from a welding rod or electrode, the head seams being formed between the plates and the outer and under sides of the rail heads and the base seams being formed between the side surface of the plates and the top 50 surface of the rail base.

It will be understood by those skilled in the art, that by compressing the rail ends, and using joint plates which have fishing engagement with the rail heads and bases, 55 I provide in the joint an additional compression at the abutted ends of the rail heads which co-operates with the plates in resisting stresses set up by loads which cause the rail joint to act as a beam and that by providing this additional compression, the strength of the joint is correspondingly increased over a joint where the rail ends are supported entirely by the plates. A further advantage in this procedure is that the rail 60 ends are held so close together that there

is no gap, and consequently no opportunity for the cold flowing of rail head metal into a gap. "Cupping" is thus substantially eliminated.

It will further be obvious to those skilled in the art that by staggering the plates I strengthen the joint, because I provide a fillet effect near the ends of the rails, thereby distributing the stresses imposed upon the rails at the ends of the joint instead of localizing the stresses in the rails at the ends of the plates as is the case where the plates are not staggered. I have further increased the strength of the joint by staggering the ends of the seam-welds with respect to each other as well as to the ends of the plates.

It will also be noted that I have provided plates which have their maximum strength at the part thereof which directly overlies the meeting faces of the rail ends, which is the point of greatest stress on the plates. In the modifications shown, this strengthening portion may be so wide that it may make it impossible or inadvisable to weld the outer surface thereof to the rail base. The strengthening portion of the plate whether welded to the rail base or not, contributes much to the strength of the plate and of the joint, because of its increased section modulus at the point of maximum stress.

It will be seen that by forming at the upper edge of each plate a rabbeted recess well beneath an adjacent rail head and extending forwardly of the edge of the rail head to constitute a ledge, I have provided a means by which large equal areas of welded contact of seam with the plate and rail may be obtained when the rails are positioned in the track and when the welding arc is directed angularly and downwardly towards the fish plate and rail, thus obtaining with greatest ease and positiveness strong welded joints.

Although I have described the use of drift pins for compressing the rail ends, other means for accomplishing the same result may be employed without departing from my invention, as for example, driving a wedge (not shown) between the ends of the assembled rails at an adjacent joint as will be readily understood.

In certain cases, it may be desirable to omit the groove 9 from the plates. This is often true when metal arc welding is employed instead of carbon arc welding. In such cases, the plates may be substantially as shown in Figs. 1 to 4 except that no groove will be formed along the upper edge of the plate.

In carrying out my method, I preferably employ prepared rail ends. The preparation of the rail ends, which may perhaps be most conveniently done at the rolling mill, comprises suitably surfacing the abutting faces of the rail ends, as for example, by

4
milling. If the webs and bases are cut back thereby leaving the heads only to contact when the rails are brought together in a joint as where it is desired to confine the mutual endwise compression to the rail heads, such preparation, surfacing or milling may be confined to the ends of the rail heads.

Although I have shown and described my invention as illustrated by certain embodiments thereof, I do not desire to be understood as limiting myself to the particular details shown and described. The scope of my invention is defined in what I claim.

15. What I claim is:

1. The method of constructing a seam welded rail joint which comprises aligning adjacent rail ends, fitting joint plates in fishing relation on opposite sides of the rail ends, bringing the rail heads directly together under moderate mutual endwise compression and integrally uniting said plates to said rail ends by head and base seam welds while said rail heads are in a state of moderate mutual endwise compression.

2. The method of constructing a seam welded rail joint which comprises aligning adjacent rail ends, fitting joint plates in fishing relation on opposite sides of the rail ends, bringing the rail heads directly together under moderate mutual endwise compression through the instrumentality of said joint plates, and integrally uniting said plates to said rail ends by head and base seam welds while said rail heads are in a state of moderate mutual endwise compression.

3. The method of constructing a seam welded rail joint which comprises aligning adjacent rail ends, fitting joint plates in fishing relation on opposite sides of the rail ends, each plate having a surface along the top edge thereof extending well beneath the adjacent rail head to form a recess and extending forwardly of the said head to form a ledge, bringing the rail heads directly together under moderate mutual endwise compression, disposing weld metal in each said recess and on each said ledge to form seam welds integrally uniting the adjacent rail heads and plates, and forming base seam welds integrally uniting the rail bases and plates.

4. The method of constructing a seam welded rail joint which comprises aligning adjacent rail ends, fitting in fishing relation on opposite sides of the rail ends joint plates having holes therethrough, said holes being slightly unaligned with respect to corresponding holes in the rail ends, bringing the rail heads together under moderate mutual endwise compression by driving drift pins through the slightly unaligned holes in the plates and rail ends,

and integrally uniting said plates to said rail ends by head and base seam welds.

5. The method of constructing a seam welded rail joint which comprises aligning adjacent rail ends, fitting in fishing relation on opposite sides of the rail ends joint plates having holes therethrough, said holes being slightly unaligned with corresponding holes in the rail ends, said plates each having a seam weld metal receiving surface along the top edge thereof extending well beneath the adjacent rail head to form a recess and extending forwardly of the said head to form a ledge, driving drift pins through the slightly unaligned holes in the plates and rail ends to bring the rail heads together under moderate mutual endwise compression, and fusing with the electric arc adjacent portions of the rail head and the upper surface of each plate and fusing therewith additional metal to form a seam weld disposed in the recess and on the ledge and integrally united to the rail head and plate, and forming seam welds integrally uniting the plates and rail bases.

6. The method of constructing a seam welded rail joint which comprises aligning adjacent rail ends, fitting in fishing relation on opposite sides of the rail ends joint plates having holes therethrough, said holes being slightly unaligned with respect to corresponding holes in the rail ends, each said plate having a surface along the top edge thereof extending well beneath the adjacent rail head to form a recess and extending forwardly of the said head to form a ledge, driving drift pins through the slightly unaligned holes in the plates and rail ends to bring the rail heads together under moderate mutual endwise compression, fusing with the carbon arc adjacent portions of the rail head and the upper surface of each plate and fusing therewith additional metal from a welding rod to form a seam weld disposed in the recess and on the ledge and integrally united to the rail heads and plates, and forming seam welds integrally uniting the plates and rail bases.

7. The method of constructing a seam welded rail joint which comprises aligning adjacent rail ends, fitting joint plates in fishing relation on opposite sides of the rail ends, the portions of said plates bridging the rail ends being strengthened at their bases, bringing the rail heads directly together under moderate mutual endwise compression through the instrumentality of the said joint plates, and integrally uniting said plates to said rail ends by head and base seam welds while said rail ends are in a state of moderate mutual endwise compression.

8. The method of constructing a seam welded rail joint which comprises aligning

- 1 adjacent rail ends, fitting in fishing relation on opposite sides of the rail ends joint plates having their ends unaligned and surfaces along the top edges thereof extending well beneath an adjacent rail head to form a recess and extending forwardly of said head to form a ledge, the portions of said plates bridging the rail ends being provided with strengthened portions, bringing the rail heads together under moderate mutual endwise compression, forming with an electric arc seam welds disposed in the recesses and on the ledges and integrally united to the rail heads and plates, and forming base seam welds integrally uniting the plates and rail bases at opposite sides of said strengthened portions of said plates, all of said seam welds stopping short of the ends of the plates, and the ends of said seam welds being staggered with respect to each other. 9. A seam welded rail joint comprising aligned adjacent rail ends having their heads under direct mutual endwise compression, joint plates arranged on opposite sides of the rail ends engaging the heads and bases of the rails in fishing relation and seam welds uniting the plates to the rail heads and base seam welds uniting the plates to the rail bases. 10. A seam welded rail joint comprising aligned adjacent rail ends, joint plates arranged on opposite sides of the rail ends engaging the heads and bases of the rails in fishing relation, each said plate having a surface along the top edge thereof extending well beneath the adjacent rail head to form a recess and extending forwardly of the said head to form a ledge, seam weld metal in each said recess and on each said ledge integrally united to the said plates and rail heads and base seam welds integrally uniting the rail bases and the plates. 11. A seam welded rail joint comprising aligned adjacent rail ends, joint plates arranged on opposite sides of the rail ends engaging the heads and bases of the rails in fishing relation, each said plate having a surface along the top edge thereof extending well beneath the adjacent rail head to form a recess and extending forwardly of the said head to form a ledge, seam weld metal in each said recess and on each said ledge integrally united to substantially equal areas of the said plates and rail heads, and base seam welds integrally uniting the rail bases and the adjacent portions of the plates. 12. A seam welded rail joint comprising aligned adjacent rail ends having their heads under mutual endwise compression, joint plates arranged on opposite sides of the rail ends engaging the heads and bases of the rails in fishing relation, each said plate having a surface along the top edge thereof extending well beneath the adjacent rail head to form a recess and extending forwardly of the said head to form a ledge, seam weld metal in each said recess and on each said ledge integrally united to substantially equal areas of each said plate and rail head, said seam welds stopping short of the ends of the plates, and base seam welds integrally uniting the rail bases and the plates and extending from each side of the base strengthening portion thereof extending well beneath the adjacent rail head to form a recess and extending forwardly of the said head to form a ledge, seam weld metal in each said recess and on each said ledge integrally united to the said plates and rail heads, and base seam welds integrally uniting the rail bases and the plates. 13. A seam welded rail joint comprising aligned adjacent rail ends, joint plates arranged on opposite sides of the rail ends engaging the heads and bases of the rails in fishing relation, each said plate having a web portion with holes therethrough and a surface along the top edge thereof extending well beneath the adjacent rail head to form a recess and extending forwardly of the said head to form a ledge, an outwardly extending flange at the lower edge of the web portion adapted to engage and be welded to a rail base, the said flange having a lateral extension between the ends of the plates extending beyond the rail base adjacent to the rail ends, seam weld metal in each said recess and on each said ledge integrally united to the said plates and rail heads and base seam welds integrally uniting the rail bases and the plates. 14. A seam welded rail joint comprising aligned adjacent rail ends, joint plates arranged on opposite sides of the rail ends engaging the heads and bases of the rails in fishing relation, each plate having a surface along the top edge thereof extending well beneath the adjacent rail head to form a recess and extending forwardly of the said head to form a ledge, the portion of each plate bridging the rail ends being of increased section modulus, seam weld metal in each said recess and on each said ledge integrally united to the said plates and the rail heads and base seam welds integrally uniting the said plates and the rail bases. 15. A seam welded rail joint comprising aligned adjacent rail ends having their heads under mutual endwise compression, joint plates arranged on opposite sides of the rail ends engaging the heads and bases of the rails in fishing relation and with their ends unaligned, each plate having a surface along the top edge thereof extending well beneath the adjacent rail head to form a recess and extending forwardly of the said head to form a ledge, the base portion of each plate bridging the rail ends being provided with an outwardly extending strengthening portion, seam weld metal in each said recess and on each said ledge integrally united to substantially equal areas of each said plate and rail head, said seam welds stopping short of the ends of the plates, and base seam welds integrally uniting the rail bases and the plates and extending from each side of the base strengthening portion

6 towards the ends of the plates but stopping short thereof.

16. A seam welded rail joint comprising aligned adjacent rail ends having their heads under mutual endwise compression, joint plates arranged on opposite sides of the rail ends engaging the heads and bases of the rails in fishing relation and with their ends unaligned, each plate having a surface 10 along the top edge thereof extending well beneath the adjacent rail head to form a recess and extending forwardly of the said head to form a ledge, the base portion of each plate bridging the rail ends being provided with an outwardly extending strengthening portion, seam weld metal in each said recess and on each said ledge integrally united to substantially equal areas of the said plates and heads, said seam welds stopping short of the ends of the plates, and base seam welds integrally uniting the rail bases and the plates and extending from each side of the base strengthening portion towards the ends of the plates but stopping short 20 thereof, all of said head and base seam welds ending in different vertical planes.

17. A joint plate for a welded rail joint having a top surface adapted to form a recess between a rail head and the plate, and to project forwardly from the rail head to form a ledge when the plate is assembled with a rail to form a rail joint.

18. A joint plate for a welded rail joint having a top surface adapted to form a substantially horizontal recess between a rail 30

head and the plate and to project forwardly from the rail head to form a ledge when the plate is assembled with a rail to form a rail joint.

19. A joint plate for a welded rail joint having a base portion strengthened intermediate its ends, said strengthened portion adapted to bridge the rail ends, said plate being adapted to engage in fishing relation with the under surface of a rail head and the upper surface of a rail base, and having a top surface adapted to form a recess with the under side of a rail head and to project forwardly from the rail head to form a ledge when the plate is assembled with a 40 rail to form a rail joint. 45

20. A joint plate for a welded rail joint adapted to engage in fishing relation with the under surface of a rail head and the upper surface of a rail base, said plate having a top surface adapted to form a recess between a rail head and the plate and to project forwardly from the rail head to form a ledge when the plate is assembled with a rail to form a rail joint, said plate having a 50 flange at the lower edge of the web portion adapted to engage and be welded to a rail base, the said flange having a lateral extension between the ends of the plate adapted to extend beyond a rail base when the plate is 55 in assembled relation therewith. 60

In testimony whereof I hereunto affix my signature this 21st day of January, 1924.

ROY B. FEHR.
